HOLD-BACK BRACKET FOR CURTAINS

James H. Boye, Chicago, Ill., assignor to James H. Boye Manufacturing Company, Chicago, Ill., a corporation of Illinois

Application November 2, 1939, Serial No. 302,493

6 Claims. (Cl. 156—33)

This invention relates to the general art of curtain fixtures, and has reference more particularly to devices that are attached to the vertical side members of a window or door frame and serve the purpose of supporting the curtains in parted relation, the lower portions of the curtains being gathered and hung over the hold-back brackets from which they are suspended at opposite sides of the window or door.

10 These brackets are commonly made in the form of generally U-shaped members, each comprising a metal shank adapted for attachment in a more or less oblique position to the window or door frame and formed with a forwardly projecting U-shaped lower end that seats the gathered portion of the curtain, and a so-called "ornament" forming the front limb of the bracket that is attached to the front limb of the U-shaped lower end of the shank member. These ornaments are 15 usually of colored glass molded in various ornamental patterns, and the lower end portion or shank of the glass ornament is fastened to the front limb of the U-shaped lower end of the metal shank member of the bracket by a clamp bolt 20 passed through registering holes in the attached parts. The ornament is of highly frangible material, and it frequently happens that in tightening the bolt the glass of the ornament is splintered or cracked in the region of the bolt hole, and 25 sometimes the stem or shank of the ornament is completely broken off. This is due mainly to the fact that the pressure of the bolt head is localized in the region of the bolt hole.

It is the main object of the present invention to 30 provide an improved fastening for the ornament that will entirely eliminate this danger of splintering, cracking and breaking the ornament and the waste consequent thereon, and this object is attained by an improved construction by which 35 the clamping pressure is uniformly distributed over the entire area of the portion of the ornament engaged by the metal shank member.

Another object of the invention is to provide 40 an improved ornament holder that will effectively prevent any side play of the ornament relatively to the part of the bracket to which it is attached.

A practical and approved embodiment of the 45 invention is illustrated in the accompanying drawing, in which—

50 Fig. 1 is a front elevation of a portion of a side member of a window frame and a curtain, showing my improved hold-back bracket attached to the frame, and the curtain gathered and hung over the bracket.

Fig. 2 is a top plan on an enlarged scale, viewed on the line 2—2 of Fig. 1.

Fig. 3 is a perspective group view, showing the parts of the ornament fastening in endwise separated relation.

Fig. 4 is a cross-section on the line 4—4 of Fig. 2.

Fig. 5 is a perspective view illustrating a modified form of one of the ornament fastening parts.

In the drawing 10 designates a portion of a 10 vertical side member of a window frame, and 11 designates a portion of a curtain suspended from a top curtain rod or pole (not shown). My improved curtain hold-back bracket comprises a narrow metal shank member 12 formed with a 15 rearwardly offset upper portion 12' apertured to receive fastening screws 13 by which the bracket is attached to the frame member 10, usually in the inclined or oblique position illustrated in Fig. 1. The shank 12 is formed with an integral forwardly projecting U-shaped lower end designated as a whole by 14, the front limb of which, designated by 15, is substantially parallel with the main portion 12.

In the preferred form of the invention there is 20 spot welded to the front side of the limb 15 a presser plate 16 of considerably greater width than the limb 15. Loosely embracing the limb 15 and presser plate 16 is a collar preferably having the form best shown in Figs. 3 and 4 and 25 comprising a back plate 17, forwardly projecting side flanges 18, and in-turned lips 19 on the free vertical edges of the flanges 18; all these parts being integral. In the back plate 17 is a central 30 tapped hole 20 adapted to receive a thumb screw 35 21.

22 designates the glass ornament, the lower end portion 22' of which is slightly narrowed to fit 40 between the side flanges 18 of the collar, as shown in Fig. 4. After the collar has been slipped down 45 over the presser plate 16 and limb 15 the upper end portion of the latter is bent rearwardly to form a stop lug 23 which overlies the upper edge of the back plate 17 of the collar and locks the latter against displacement in an upward direction. A lower stop lug 24 spot welded or otherwise secured to the outer face of the lower curved portion 14 of the shank member of the bracket abuts at its upper end against the lower ends of the flanges 18, and thus locks the collar against 50 displacement in a downward direction. In mounting the ornament on its supporting shank member, the collar having been assembled and locked in place, the thumb screw 21 is backed off, and the shank 22' of the ornament is inserted in 55

the collar between the presser plate 16 and the lips 19 of the flanges. The thumb screw is then tightened, which clamps the shank 22' securely in the socket thus formed. The pressure of the 5 thumb screw is transmitted through the entire area of the presser plate 16 to the substantially co-extensive area of the rear side of the shank 22', thus avoiding any tendency to fracture, crack or break the shank 22'. At the same time, the 10 side flanges 18 very securely support the ornament against any lateral looseness or side play. If a new ornament is to be substituted, a mere backing off of the thumb screw 21 is all that is necessary to withdraw the old ornament and 15 substitute the new one.

In Fig. 5 I illustrate a slight modification, wherein the presser plate 16', instead of being a separate element spot welded to the limb 15, is made as a widened portion of said limb co-extensive in area with the presser plate 16. This construction is slightly simpler than that of Figs. 1-4 but is slightly more costly than the latter, for the reason that the waste of metal involved in making the structure of Fig. 5 more 20 than balances the slight additional cost of making and attaching presser plate 16. It will be evident that in the structure of Figs. 1-4 the entire shank member 12, 14, 15 can be cut in suitable lengths from a continuous strip of sheet metal, and bent 25 to shape; whereas the structure of Fig. 5 requires a strip of metal the full width of the presser plate 16', with the excess width cut off and discarded in all except the presser plate region. The operative principle of Fig. 5, is however, identical with 30 that of Figs. 1-4, and is fully within the purview of the invention as defined in the claims.

Changes and modifications in the details of structure and arrangement may be resorted to within the scope and coverage of the claims.

40 I claim:

1. A curtain hold-back bracket, comprising a metal shank member adapted to be attached at its upper end portion to a side member of a window or like frame and formed with a forwardly 45 projecting U-shaped lower end, a clamp collar loosely embracing the front limb of said lower end and having a tapped hole in its rear side, a frangible ornament having its lower end portion inserted between said collar and said front limb, 50 and a clamp screw engaged with said tapped hole and bearing against the rear side of said front limb.

2. A curtain hold-back bracket, comprising a metal shank member adapted to be attached at its upper end portion to a side member of a window or like frame and formed with a forwardly projecting U-shaped lower end, a clamp 5 collar loosely embracing the front limb of said lower end, said collar comprising a back plate having a tapped hole therein and integral forwardly projecting side flanges formed with inwardly turned lips, a frangible ornament having 10 its lower end portion inserted between said lips and said front limb, and a clamp screw engaged with said tapped hole and bearing against the rear side of said front limb.

3. In combination with the subject-matter defined in claim 1, upper and lower stops on the U-shaped lower end of the shank member overlying the upper and lower edges of the collar to confine the latter against vertical displacement.

4. In combination with the subject-matter defined in claim 2, a rearwardly extending stop lug on the upper end of the front limb of the U-shaped lower end of the shank member overlying the upper edge of the collar, and a stop member on the lower portion of said front limb 20 underlying the lower edges of the side flanges of the back plate.

5. A specific embodiment of the subject-matter defined in claim 1, wherein the metal shank member is narrower than the lower end portion 30 of the ornament, and a presser plate of a width equal to the width of the lower end portion of the ornament is secured to the front side of the front limb of the U-shaped lower end of the metal shank member to transmit the thrust of the clamp 35 screw to the entire area of the ornament engaged by said presser plate.

6. A specific embodiment of the subject-matter defined in claim 1, wherein all of the metal shank member except the portion embraced by the collar is narrower than the lower end portion of the ornament, and the said portion embraced by the collar has a width equal to the width of the lower end portion of the ornament, whereby the thrust of the clamp screw is transmitted to the entire area of the ornament engaged by the said widened portion of the shank member embraced by the collar.

JAMES H. BOYE. 50
